(57) **CLAIM**

We claim the ornamental design for a cover for an electronic device, as shown and described.

DESCRIPTION

FIG. 1 is a front perspective view of a cover for an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an exploded view of the cover for an electronic device in which a camera lens is shown in broken lines to illustrate an example environment.

(Continued)

The broken lines in the figures depict environmental subject matter and form no part of the claimed design.
